UNITED STATES PATENT OFFICE.

JENS N. MILLER, OF SAN FRANCISCO, CALIFORNIA.

GRAIN-HARVESTER.

SPECIFICATION forming part of Letters Patent No. 394,989, dated December 25, 1888.

Application filed August 13, 1887. Serial No. 246,911. (No model.)

To all whom it may concern:

Be it known that I, JENS N. MILLER, of the city and county of San Francisco, State of California, have invented an Improvement in 5 Grain-Harvesters; and I hereby declare the following to be a full, clear, and exact description of the same.

My invention relates to certain improvements in harvesters of that class in which a 10 comb projects in front and takes off the heads of the grain, while a revolving beater receives and thrashes these heads as they pass backward from the comb; and my invention consists in the constructions and combinations of 15 devices, which I shall hereinafter fully describe and claim.

Figure 1 is a perspective view of the apparatus with a part of the cover broken away. Fig. 2 is a longitudinal vertical section of the 20 same, showing the interior. Fig. 3 is a view of the adjusting-screw and the rack and locking devices. Fig. 4 is an enlarged view of two of the comb-teeth, showing their construction and shape. Fig. 5 is an enlarged sectional view showing a portion of the inclined chute, one of the comb-teeth, and the beater-shaft and beaters.

In the drawings, A A represent the main bearing-wheels upon the axle A'; and B is the 30 main casing supported thereon, said casing being constructed of any suitable material, having its rear portion adapted to receive the grain and its front portion extending forward of the bearing-wheel. In the forward portion 35 of the casing B a transverse shaft, 2, is suitably journaled, and on said shaft the beaters D are secured in any well-known manner. At the extremity of the front portion of the casing the comb C is permanently or otherwise 40 secured and supported, said comb being composed of long teeth or fingers 3, as I shall hereinafter fully describe.

A narrow platform, E, extends forward in line with the left-hand bearing-wheel A, being 45 connected with the axle thereof by bars F, and its front end is supported by a small steering-wheel, G. The bars F connect the rear end of the platform E with the main axle, the ends of which are permitted to turn in the 50 ends of said bars when the comb and front of the machine are raised or lowered by mech-

anism hereinafter described. From the lower part of the casing B a stout arm or bar, H, extends beneath the platform E, and has a curved rack, I, fixed in its forward end and extending up through a slot in the platform, the upper end being connected with the casing B and supported therefrom by a stout brace-rod, J.

K is a cylindrical housing, bolted upon the 60 top of the platform E and inclosing a worm, L, which meshes with the curved rack I, and by means of a crank-arm, M, upon the upper end of this worm-shaft it may be turned so as to raise or lower the rack, and with it the 65 front end of the machine which carries the comb.

In order to lock the worm and hold it at any proper or desired point a grooved collar, N, is fitted to slide vertically upon a spline or 70 feather on the worm-shaft, and is pressed down by a spiral spring, O. Upon the lower flange of this collar is a downwardly-projecting lug, P, which engages in corresponding notches or depressions upon the top of the 75 housing K, as is shown in Fig. 6, and thus prevents the worm from rotating. When it is desired to turn the worm in either direction, the collar N is raised by means of a lever, R, and the shaft then turned by means 80 of its crank arm or lever, so as to raise or lower the front of the machine, as is desired.

The comb is composed of long teeth or fingers 3, made of sheet metal, the middle portion, 4, of each being slightly concaved or 85 trough-shaped, while the forward portions are cylindrical in cross-section and taper to points, as shown in Figs. 4 and 5. The rear portions of the teeth or fingers are made flat, whereby they may be secured by bolts or 90 otherwise to the front end of the main casing, and said teeth sever the heads of the grain as they come in contact therewith, both before and when struck by the beaters D. These comb-teeth also curve upwardly at C' in the 95 line of their length or from the point of attachment to the casing or frame toward the points where they are closed. This curvature C' is made in the arc of a circle, which is concentric with the circle described by the beaters D, which enable them to follow closely the curvature of the comb-teeth, and thus sweep 100

- the grain and heads which are severed backward, the force of the percussion given by the beaters serving to separate to a great extent the grain from the husks. The closed 5 conical points of the teeth prevent the grain from sliding off toward the front when the forward portion of the machine is considerably depressed, as in low grain. The rapid revolution of the beaters D, striking the grain 10 in the curved portion C' of the comb-teeth, separates it from the chaff, and at the same time it forces the whole backward and upward through the inclined chute S to the upper front portion of the casing B. At this 15 point a thrashing-cylinder, T, is journaled, and a corresponding toothed bar, U, is fixed beneath this cylinder, so that the chaff, the grain, and any unthrashed heads pass through this thrashing mechanism where the work is 20 completed.
- Beneath the toothed bar U is a fan-casing containing a fan, V, and the blast of air from this fan is delivered through the opening W, just above the screen Y, upon which the grain 25 and heads fall after leaving the thrashing-cylinder. This blast of air is sufficient to blow out nearly all of the chaff through the upper rear portion of the machine and allow the grain thus partially cleaned to fall into 30 the lower portion of the casing B.
- Z is a curved direction board or plate, which throws the grain and husks downward upon the screen G after leaving the thrashing-cylinder.
- 35 The mechanism for driving the beaters D and the thrashing-cylinder T consists of pulleys *a* upon the ends of their respective shafts, and a belt, *b*, passing over these pulleys from a pulley, *c*, serves to drive them at the desired rate of speed. The pulley *c* is fixed 40 upon a shaft having a pinion, *d*, upon its opposite end, and this pinion engages with a gear-wheel, *e*, fixed upon the left-hand bearing-wheel A.
- 45 Having thus described my invention, what I claim as new, and desire to secure by Letters Patent, is—
1. An improved harvester comprising the box or casing supported upon the axle of the 50 bearing-wheels, a rotary beater, a comb projecting from the front of the casing and having the rear portion of its teeth made concave

in transverse section and corresponding longitudinally with the curve of the circle of the beater, the upwardly-inclined chute through 55 which the grain is forced by the momentum given it by the beater, a thrashing-cylinder, and stationary thrashing-teeth at the upper rear end of said chute, and means for operating the beater and cylinder, substantially 60 as herein described.

2. The comb or gatherer projecting from the front of the machine, having the rear portion of the teeth made concave in transverse section and corresponding with the curve of 65 the circle of the beater in longitudinal section, and having the conically-formed points, substantially as herein described.

3. The combination of the comb having the rear portion of the teeth made concave in 70 transverse section, and said teeth being also curved longitudinally, as described, a beater above and at the rear of the comb and rotating in the curved portions of said comb-teeth, an upwardly and backwardly inclined chute 75 through which the grain and chaff are forced from the beater, a thrashing-cylinder and stationary thrashing-teeth at the upper rear end of said chute, a directing-plate and screen for receiving the grain and chaff, and a fan, sub- 80 stantially as herein described.

4. The main wheels, the casing supported thereon and carrying the gathering-comb at its front end, the beater, and the thrashing-cylinder, the platform E, and the rack passing through said platform and rigidly connected with the casing, in combination with a screw the shaft of which is journaled upon the platform, so that the screw engages the teeth of the rack, a crank-arm by which the 90 screw is turned to raise or lower, and gathering-comb, and the locking mechanism composed of the spring-actuated collar sliding upon the screw-shaft and having lugs to engage corresponding notches in the screw case 95 or frame, and the lever by which it is disengaged, substantially as herein described.

In witness whereof I have hereunto set my hand.

JENS N. MILLER.
